LOADING AND FEEDING APPARATUS FOR
COILS OF STRIP METAL

Frank J. Wood, Riverside, Ill., assignor to Goodman Manufacturing Company, Chicago, Ill., a corporation of Illinois

Original application June 8, 1944, Serial No. 539,368. Divided and this application December 11, 1944, Serial No. 567,760

2 Claims. (Cl. 242—78)

1

This invention relates to improvements in loading and feeding apparatus for coils of strip metal.

Heretofore coils of strip metal have been loaded onto rotatable expandable coil supporting blocks or mandrels by power, by mounting the coil on a movable carriage and elevating the coil so its open center can be moved onto the mandrel. The mandrel is then expanded after the coil has been fully mounted thereon. As the coil is loaded onto the mandrel, its tail end, which projects outwardly from the coil, is moved sideways with the coil between a pair of pinch rolls. These pinch rolls are adapted to grip said tail end of the coil and feed it to a cropping shear, or a processing apparatus such as a roll stand, slitter, brushing unit, pickling and cleaning unit, or any other type of processing apparatus. The pinch rolls frequently grip the metal and unwind the coil before it is fully expanded. This causes the coil to spring and unwind to such an extent that the mandrel cannot be sufficiently expanded to fully grip the inside of the coil, resulting in further springing and unwinding of the coil and making it necessary to remove and rewind the coil before processing.

Among the objects of my invention are to provide a novel and improved form of loading and feeding means for coiled strip metal wherein the coil is loaded onto an expandable mandrel by power, and in so interlocking the pinch rolls with the mandrel that the pinch rolls cannot be engaged with the leading end of the metal until the mandrel is fully expanded.

This application is a division of application Serial No. 539,368, filed by me on June 8, 1944.

Other objects of my invention will appear from time to time as the following specification proceeds and with reference to the accompanying drawings wherein:

Figure 1 is a top plan view of a coil feeding and loading device constructed in accordance with my invention;

Figure 2 is a view in side elevation of the device shown in Figure 1;

Figure 3 is a fragmentary substantially longitudinal sectional view showing certain details of the coil loading device and the pinch roll stand for feeding the coil for processing;

Figure 4 is an enlarged transverse sectional view taken through the pinch roll stand, in order to show the adjusting and drive means for the pinch rolls;

Figure 5 is a plan view of the pinch roll stand with certain parts thereof shown in horizontal section; and

2

Figure 6 is a diagrammatic view showing the fluid system for operating the coil loading and feeding means of my invention.

In the drawings, an expandable mandrel 10 is shown as being rotatably mounted on a base frame 12 at the entering end of a pair of pinch rolls 11, 11. Said mandrel serves to support a coil of strip metal 15 for unwinding, and said pinch rolls serve to grip and unwind the strip metal and feed it to a suitable processing device such as a flying shear 13, which is adapted to crop the ends thereof, before the metal passes to a pickling and cleaning device or other processing apparatus (not shown). Said flying shear is shown in the drawings for illustrative purposes only and is no part of my present invention so will not herein be shown or described in detail.

The base frame 12 is mounted on a suitable foundation and includes a pair of parallel spaced 20 connected I-beams 16, 16 extending parallel to the axis of the mandrel 10. Said mandrel is suitably mounted on said base frame in a mandrel housing 17 and extends along said frame between said I-beams. Said mandrel housing is mounted 25 on the top sides of said I-beams and projects upwardly therefrom, and said mandrel is journaled in said mandrel housing in overhanging relation with respect thereto, so the open center of the coil of strip metal 15, carried on a coil supporting carriage 18, may be placed on its free end.

The expanding mandrel 10 may be of any well known form and is not herein shown or described in detail, since its detailed construction forms no part of my present invention. Figure 6 of the drawings diagrammatically shows this mandrel as including a plurality of segments 22, 22 expanded by wedges 23 and 24, which are actuated by a fluid cylinder 25 and piston 26 through a piston rod 27. The admission of fluid under pressure to the head end of said cylinder causes the wedges 23, 24 to coact with the segments 22, 22, to expand said mandrel outwardly to engage the interior of the coil of strip metal 15.

During the operation of centering and loading 45 the coil 15 onto the mandrel 10, the tail end of the coil, which is its leading end when being paid off of the mandrel 10, projects in a direction towards the pinch rolls 11, 11 and rests on an inclined guide plate 95. Said inclined guide 50 plate is mounted on the pinch roll stand and extends in a horizontal direction away from the entering end of said pinch roll stand to a position in alignment with the carriage 18, when said carriage is in position to receive a coil. During 55 movement of the carriage 18 towards the mandrel

10, said tail end of the coil will slide along the upper surface of said guide plate and beneath a guide plate 95, extending in the direction of said guide plate 95 and mounted above said guide plate on said pinch roll stand, and will be guided by said guide plates between the pinch rolls 11, 11.

The lower pinch roll 11 is mounted adjacent its opposite ends in suitable bearing supports 99, 99, projecting upwardly from a bottom plate 100 of a frame 101 of the pinch roll stand. Said frame is of a substantially C-shaped formation opening towards the guide plates 95 and 98, to permit the insertion of the tail end of the coil between said pinch rolls as the coil is loaded onto the mandrel 10. The upper portion of said frame 101 is provided with a pair of laterally spaced vertically extending channelled guides 102, 102, within which is guided a frame 103 having the upper pinch roll 11 suitably journaled therein, adjacent its opposite ends. A piston rod 104 extensible from a cylinder 105 is secured to the frame 103 for moving said frame vertically, to engage the upper pinch roll 11 with the upper surface of the metal and to pay the metal off of the mandrel 10 upon rotation of said pinch rolls.

The pinch rolls 11, 11 are both driven from a motor 106 mounted on a support bracket 107, herein shown as being yieldably connected to the frame 101 and projecting laterally therefrom. Said motor has drive connection with a worm 109 through a suitable drive connection which is herein shown as being a V-belt drive indicated generally by reference character 110. The worm 109 meshes with a worm gear 111 on a shaft 112 substantially coaxial with the lower roll 11. Said shaft 112 has connection with the lower pinch roll 11 by means of a flexible drive connection indicated by reference character 114, herein shown as being a well known form of roller mill drive connection. A spur gear 115 on the shaft 112 meshes with and drives a spur gear 116 on a parallel shaft 113. Said shaft is flexibly connected with the upper pinch roll 11 by means of a suitable roller mill drive connection 117.

Referring now in particular to the fluid diagram shown in Figure 6 and the interlocking connection between the mandrel 10 and the cylinder 105 for engaging the pinch rolls with the strip metal, a control valve 119 is provided to control the admission and release of fluid under pressure to the cylinder 25, for expanding and retracting the mandrel 10. Said control valve is connected with a fluid pump 120 by means of a pressure line 121. A return line 122 leads from said control valve to a fluid storage tank 123. A pressure line 124 leads from said control valve to the piston rod end of the cylinder 25, to supply fluid under pressure to said end of said cylinder and move the wedges 23 and 24 in a direction to permit said mandrel to retract. A relief valve 125 is provided in said pressure line to relieve excessive pressures from said pressure line and said cylinder 25. A pressure line 127 leads from the control valve 119 to a speed control valve 128. A pressure line 129 leads from said speed control valve to the head end of the cylinder 25 for supplying fluid under pressure thereto, to move the wedges 23 and 24 in a direction to expand the mandrel 10. The speed control valve 128 may be a reduced return valve of a well known form, to restrict the passage of fluid from the head end of said cylinder to the return, to retard the speed of travel of the piston 26 when moving in a direction to permit said mandrel to contract.

A pressure line 130 connects the pressure line 76

129 with a by-pass valve 131. A pressure line 133 connects said by-pass valve with a control valve 134. A return line 135 connects said control valve with the tank 123. A pressure line 136 connects 5 said control valve with the head end of the cylinder 105, to supply fluid under pressure thereto and to move the upper pinch roll in a direction to engage the upper surface of the strip metal and to hold said pinch roll in engagement therewith. 10 A pressure line 137 connects the control valve 134 with a speed control valve 139. A pressure line 140 connects said speed control valve with the piston rod end of the cylinder 105, for supplying fluid under pressure thereto and moving the 15 upper pinch roll 11 in a direction to release pressure from the upper surface of the metal. Said speed control valve like the speed control valve 128 may be a reduced return valve, and is provided to reduce and control the speed of engagement of the upper pinch roll with the strip metal upon the application of fluid under pressure to the head end of the cylinder 105. The by-pass valve 131 is provided to hold pressure in the line 130 until a predetermined pressure is reached 20 therein, at which time the mandrel 10 will be in a fully expanded condition and will be held in engagement with the inside of the coil 15. Said by-pass valve may be of any well known form arranged to prevent the flow of fluid under pressure to and through the pipe 133 until a predetermined pressure is reached in the valve and, as herein shown, includes a plunger 142 seated in a passageway 143. When a predetermined pressure is reached in a passageway 144 of said valve, said plunger will be lifted off its seat and fluid will flow through the passageway 143 into chamber 145, and out the pipe 133 to the control valve 134. This valve therefore prevents the upper pinch roll 11 from being moved into engagement with the upper surface of the metal until the mandrel 10 has been fully expanded.

A pump 141 is provided to supply fluid under pressure to the head and piston rod ends of cylinders 61 and 47. Said pump and cylinders, and the fluid connections thereto and the mechanisms which said cylinders operate, form no part of my present invention and are more particularly described in my parent application Serial No. 539,368, so need not herein be shown or described further.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a device for feeding strip metal and in combination with a rotatable expanding mandrel, means for expanding said mandrel into engagement with the inside of a coil of strip metal, two power driven pinch rolls for engaging the leading end of the coil of strip metal and feeding the strip metal for processing, and means for moving said pinch rolls into engagement with the strip metal, said means being interconnected with said means for expanding said mandrel, to prevent said pinch rolls from being engaged with the strip metal until said mandrel is in a fully expanded condition.
2. In a device for feeding strip metal and in combination with a rotatable expanding coil sup-

porting mandrel, fluid means for expanding said mandrel into engagement with the inside of a coil of strip metal, two power driven pinch rolls for engaging opposite sides of the leading end of the coil of strip metal and feeding the strip metal for processing, fluid means for moving said pinch rolls into engagement with the strip metal and holding them in engagement therewith, and an

interlocking connection between said means for expanding said mandrel and said means for engaging said pinch rolls with the strip metal, arranged to prevent said pinch rolls from engaging the strip metal until said mandrel is in a fully expanded condition.

FRANK J. WOOD.
